UNITED STATES PATENT OFFICE.

HERMAN BARDITZKY, OF FLORENCE, ALABAMA.

COTTON-SEED-DELINTING MACHINE.

SPECIFICATION forming part of Letters Patent No. 662,337, dated November 20, 1900.

Application filed April 26, 1900. Serial No. 14,477. (No model.)

To all whom it may concern:

Be it known that I, HERMAN BARDITZKY, a citizen of the United States, residing at Florence, in the county of Lauderdale and State 5 of Alabama, have invented certain new and useful Improvements in Cotton-Seed-Delinting Machines; and I do hereby declare the following to be a full, clear, and exact description of the invention, such as will enable 10 others skilled in the art to which it appertains to make and use the same.

My invention relates to that class of machines employed for removing the lintor fiber from cotton-seed after it leaves the gin, and 15 well known as "delinting-machines."

The object of the invention is to generally make the construction of such machines with a view to greater capacity, economical construction, simplicity, and rapidity of operation. 20

With this object in view the invention consists in the improved construction, arrangement, and combination of the parts of a machine of this class, which will be hereinafter fully described and afterward specifically 25 claimed.

In the accompanying drawings, Figure 1 is a longitudinal vertical sectional view, parts being shown in elevation. Fig. 2 is a transverse vertical sectional view. Fig. 3 is a detail perspective view illustrating the teeth-plate securing and adjusting mechanism. 30

Wherever the same parts occur in the different figures they are indicated by the same 35 reference-numerals.

Referring to the drawings by numerals, 1 indicates the main body or casing of the machine, which may be made of any suitable material and is intended to inclose the principal parts of the machine. Surmounted upon 40 the main casing is a seedbox 2, having vertical side and end walls, the front side walls 3 being provided at their lower ends with a series of horizontally-projecting steel teeth 4, 45 said teeth being either formed integral with the metal plate forming this wall or they may be made separate and secured thereto in any suitable manner. Journaled in suitable bearings 4 in the end walls of the seedbox is a 50 horizontal shaft 5, which is provided with solid radial blades 6, preferably four in number, and located in pairs at right angles to

each other, said blades extending the greater portion of the length of the shaft, the remainder of the shaft being provided with radially-arranged and "staggered" stirring-teeth 7. The seedbox is covered, except for that portion in which the stirrer-teeth are located, above which latter portion is mounted a hopper 8. 55

In the main frame 1 beneath the open bottom of the seedbox is journaled the horizontal main shaft 9, upon which is mounted an abrading-roller 10, preferably covered with card-clothing, which roller is so located that 65 its periphery during its rotation will pass in close proximity to the points of the teeth 5 and also in close proximity with the lower end of the rear wall of the seedbox.

The front plate 3 of the seedbox which carries the teeth 4, as above stated, is supported by means of a right-angled bracket 11, secured to the plate by a bolt 12 and to a horizontal flange 13, projecting inwardly from the top of the main casing by a bolt 14, one 75 of the openings for each of the bolts being enlarged, so as to permit of the horizontal or vertical adjustment of the plate 3 and teeth 4 in order to secure the teeth in proper position relative to the periphery of the abrading-roller. 80

Within the main casing, in substantially the same horizontal plane as the main shaft 9, is journaled a shaft 15, on which are mounted fan-blades 16. 85

Below the roller 10, within the casing, is a second seedbox 17, the front plate 18 of which is provided with teeth 19, similar in form and position to the teeth 4 of the plate 3, and within this lower seedbox 17 is journaled a horizontal shaft 20, provided with solid radial blades 21. Immediately below the open bottom of the seedbox 17 and within the main casing is journaled a horizontal shaft 22, upon which is mounted an abrading-roller 90 23, preferably of the same form and construction as the roller 10, said roller being so located that in its rotation its periphery will pass in close proximity to the ends of the teeth 19 and the lower end of the rear wall 20 95 of the seedbox 17. The front wall 18 of the seedbox 17 is adjustably mounted on a horizontal flange 24 by means of a bracket 25 and bolts in the same manner as the front plate 100

3 of the upper seedbox is secured to the flange 13, whereby the plate 18 and teeth 19 are adjustable vertically and horizontally secure the teeth in proper position relative to the 5 periphery of the roller 23. In the main casing in front of the roller 23 is journaled a shaft 26, upon which are mounted fan-blades 27.

The lower end of the casing 1 terminates in a horizontal spout or duct 28, open on its under side to receive an endless belt 29, mounted upon and driven by suitable rollers mounted on shafts at each end of the belt, one of which is shown at 30, the outer end of the belt being broken away and the outer supporting-roller omitted. The casing is supported upon suitable legs, as at 31 32.

The seedbox 2 is provided with an opening in its end wall at the left, as shown in Fig. 1, which may be closed wholly or partially by 20 means of a sliding door 33, operated by a handle 34, to permit of the passage of seed out of the seedbox into a spout 35, by means of which the seed are conducted into the lower seedbox 17. The lower seedbox is provided 25 with a sliding door 36 at its opposite end, through which the seed is discharged into a spout 37, which may be constructed of any suitable form to properly conduct the seed to any receptacle prepared to receive it.

30 On the shaft 9 may be mounted a suitable pulley 38, from which a crossed belt 39, as indicated in dotted lines in Fig. 2, is passed to a small pulley on the shaft 15, whereby the fan-blades 16 are rotated in the direction indicated by the arrow at a higher speed than the roller 10. A small pulley 40 on the shaft 9 is connected by a belt to a large pulley 41 on the shaft 5, whereby the said shaft and the blades 6 and teeth 7 are rotated at a 40 slower speed than the roller 10. The shaft 9 is rotated from any suitable power by means of a suitable belt working on a pulley 42, and rotation in the same direction is communicated to the shaft 22 by means of a suitable belt, as indicated at 43 in dotted lines in Fig. 45 2, connecting a pulley 44 on the shaft 9 with a pulley 45 on the shaft 22.

The shaft 20, with its blades 21, and the shaft 26, with its fan-blades 27, are rotated 50 from the shaft 22, the shaft 20 slower and the shaft 26 faster than the shaft 22, by means of substantially the same arrangement of belts and pulleys as is used to rotate the shafts 5 and 15 from the shaft 9, as heretofore described, the direction of rotation of each shaft being indicated in Fig. 2 by means of arrows.

In the operation of the invention cotton-seed placed in the hopper 8 drops into the 60 seedbox in that end in which the teeth 7 will rotate, said teeth serving to stir and agitate the mass of seed. The seed is then carried around by the abrading-roller into contact with the teeth 4, which are sufficiently near together to prevent the seed dropping between them, and the abrading-roller operating upon the seed held up by the teeth will clean

the lint therefrom, the seed being kept continually in motion and rolled about upon the teeth 4 until substantially free from lint. 70 The pressure of the seed in the hopper upon that below and in the seedbox 2 will cause the seed to gradually pass along to the left over the teeth 4 until the opening at the opposite end of the roller is reached. The door 33 being opened to an extent determined by 75 experience, the seed will pass through it and through the spout 35 into the lower seedbox 17, being stirred and pressed downward during its passage through the upper seedbox 80 by the blades 6. In the lower seedbox the seed will be pressed downward and toward the plate 18 by the blades 21, and in addition will be carried by the roller in the same direction, causing the seed in the lower box to 85 lodge on the teeth 19 of the plate 18 to undergo a repetition of the treatment received in the upper seedbox, the seed gradually working its way to the opposite end of the lower seedbox and roller 23 and finally passing out 90 through the opening covered by the sliding door 36 into the spout 37, through which, as before stated, it is delivered in a perfectly clean condition to any suitable receptacle. The cotton stripped from the seed by 95 the abrading-rollers will be carried downward, as indicated by the arrows in Fig. 2, and forced along by the currents of air caused by the rotation of the fan-blades 16 and 27 until it passes upon the endless belt 28 and by it is 100 delivered through the horizontal belt into any suitable receptacle placed to receive it.

By means of the construction herein described the lint is quickly and cleanly removed from the seed, the seed delivered from 105 one end of the machine in a cleaned and polished condition, and the removed lint delivered at the rear of the machine, the whole operation being rapid and the machinery being simple and economical in construction. 110

While the specific construction of the various parts has been particularly described it will be obvious to those skilled in the art that changes and variations might be made therein without departing from the spirit and 115 scope of the invention.

Having thus described the invention, what is claimed as new, and desired to be secured by Letters Patent, is—

1. The combination in a cotton-seed-delinting machine with a suitable casing and an abrading-roller mounted therein, of a seedbox surmounting the casing and the roller, one wall of said seedbox being vertically and horizontally adjustable, and horizontal teeth 120 projecting inwardly from said adjustable wall into close proximity to the periphery of the abrading-roller, substantially as described. 125

2. The combination in a cotton-seed-delinting machine, of a main casing, an abrading-roller mounted therein, an open-bottom seedbox mounted above said casing and roller, one of the walls of said box being vertically and horizontally adjustable, teeth on the lower 130

end of the said adjustable wall extending horizontally into close proximity with the periphery of the abrading-roller, a hopper mounted above one end of the seedbox, a horizontal shaft longitudinally journaled in the seedbox, radial stirring-teeth upon said shaft below the hopper, and radial crushing and stirring blades mounted upon said shaft for the remainder of its length, substantially as described.

3. The combination with a cotton-seed-delinting machine, of a main casing, a horizontal abrading-roller journaled therein and projecting through the top thereof, an open-bottom seedbox mounted above the casing and roller, horizontally and vertically adjustable teeth mounted in close proximity to the periphery of the roller, a second open-bottom seedbox mounted in the casing below the roller, horizontal teeth therein, and a second abrading-roller mounted below the lower seedbox with its periphery in close proximity to said teeth, substantially as described.

4. In a cotton-seed-delinting machine, the combination of a main casing, an abrading-roller mounted therein and projecting through its top, an open-bottom seedbox surmounting the casing and roller, horizontally and vertically adjustable teeth in proximity to the periphery of said roller, a horizontal shaft in the seedbox above the roller provided with radial teeth and radial blades as described, a fan in the main casing in substantially the same horizontal plane as the roller, a second open-bottom seedbox mounted within the casing below the abrading-roller, a second abrading-roller mounted in the bottom of said seedbox, horizontally and vertically adjustable teeth in proximity to the periphery of said roller, and a horizontal shaft in the lower seedbox above said roller provided with pressing and stirring blades throughout its length, substantially as described.

5. The combination in a cotton-seed-delinting machine, of a suitable casing open at the top, a horizontal abrading-roll journaled therein and projecting through the top, horizontally and vertically adjustable teeth in proximity to the periphery of said roll, an open-bottom seedbox mounted over the roll, a second open-bottom seedbox within the casing and below the abrading-roll, horizontal teeth therein, a second abrading-roll horizontally journaled in the casing and projecting into the bottom of the second seedbox, a communicating passage between the first and second seedboxes at one end of the machine, a hopper above the first seedbox at the opposite end, and a discharge-opening at the hopper end of the lower seedbox, substantially as described.

6. The combination in a cotton-seed-delinting machine, of a main casing open at the top, a seedbox mounted above the opening, an abrading-roll horizontally journaled in the casing and projecting into the seedbox, vertically and horizontally adjustable teeth mounted in proximity to the periphery of the roll, a horizontal shaft mounted in the seedbox above the abrading-roll, stirrer-teeth on a portion of the length of the shaft, solid blades on the remainder of the length of the shaft, a hopper mounted above the stirrer-teeth, the seedbox being provided at its opposite end with an opening, a sliding door in said opening, and a spout leading from said opening, substantially as described.

7. The combination in a cotton-seed-delinting machine, of a main casing, an abrading-roll horizontally journaled in the upper portion thereof, a seedbox mounted above the roll, horizontally and vertically adjustable teeth in proximity to the periphery of the roll, a hopper at one end of the seedbox for receiving the seed, a sliding door at the opposite end for the discharge of the seed, a lower seedbox within the casing, an abrading-roll mounted below and projecting into said seedbox, horizontally and vertically adjustable teeth in proximity to the periphery of said roll, a sliding door at one end of the lower seedbox, a spout connecting the discharge-opening of the upper box with the receiving-opening of the lower box, a discharge-spout at the opposite end of the lower box, a fan horizontally journaled in the casing by the side of the upper roll, a second fan horizontally journaled in the casing at the side of the lower roll, means for driving each roll and its fan in opposite directions, a delivery-spout at the lower end of the casing, and an endless belt working through an opening in the bottom of the casing at said spout, substantially as described.

8. The combination in a cotton-seed-delinting machine, of a suitable casing open at the top, a horizontal abrading-roll journaled in said casing and projecting through the top thereof, an open-bottom seedbox surmounting the casing and roll, a horizontal flange on the casing projecting inward toward the roll, right-angled brackets adjustably secured upon said casing, and a teeth-bearing side wall of the seedbox adjustably connected to said brackets, substantially as described.

In testimony whereof I hereunto affix my signature in presence of two witnesses.

HERMAN BARDITZKY.
